UNITED STATES PATENT OFFICE.

CHARLES E. ADAMS, OF SCRUBGRASS, PENNSYLVANIA, ASSIGNOR OF ONE-HALF TO BRYAN
H. OSBORNE, OF FRANKLIN, PENNSYLVANIA.

PIPE-WRENCH.

No. 902,041.

Specification of Letters Patent.

Patented Oct. 27, 1908.

Application filed December 31, 1907. Serial No. 408,796.

To all whom it may concern:

Be it known that I, CHARLES E. ADAMS, citizen of the United States, residing at Scrubgrass, in the county of Venango and State of Pennsylvania, have invented certain new and useful Improvements in Pipe-Wrenches, of which the following is a specification, reference being had therein to the accompanying drawing.

10 The construction of my improved pipe wrench is herein fully set forth, reference being had to the accompanying drawings which form a part hereof and in which:—

Figure 1 is a side view of my complete wrench, Fig. 2 is a bottom view of the stock or main portion of the wrench, Fig. 3 is a perspective view of the movable jaw, Fig. 4 is a detail.

20 The same reference letters indicate identical parts in the several views.

The stock or main portion of my wrench is a unitary structure, consisting of a handle 1, a body 2, and a downwardly-curved main or resistance jaw 3. The inner face of said jaw 3,—that is the face which is in juxtaposition to the handle—is the working face of said jaw. It is this jaw which conforms to the surface of the pipe and presents the greater amount of contact surface thereto when in 25 operation, whereas, in other wrenches of this class the resistance jaw, or the one which presents the greater amount of contact surface to the pipe is a swinging jaw. The stationary resistance jaw, formed integral with 30 the stock is, therefore, a distinguishing feature of my invention, and as the term "resistance jaw" is here employed—especially in the claims—it designates the jaw which presents the greater amount of contact 35 surface to the pipe.

Within the body 2 is formed a recess 2' for the reception of a jaw-actuating block 4, and a spiral spring 5 which bears against one end of said block. Upon the lower portion of the body 2, at each side of said recess, two ears 6, 6, are formed, and adapted to the attachment of one end of a swinging pressure jaw 7, the outer, or contact face of which is in apposition and conforms approximately to the working face of jaw 3. Jaw 7 is provided at one end with a pivotal or hinge member 8, by means of which it is attached to the ears 6, 6, by means of a pin 9, which passes through said ears and said hinge member. Upon the upper face of said hinge member 8, and im-

mediately above the pivotal point thereof, is located a lug 8' which is engaged by a notch 4' in the actuating block 4. Spiral spring 5 bears against one end of said block and presses in the direction indicated by the arrow in Fig. 4. This action tends to keep the movable jaw in close contact with the pipe and causes it to grip the same firmly.

I have found it desirable to limit the gripping action of the movable jaw, so that it will not crush the pipe at times when it is necessary to exert considerable force or power upon the wrench, and for this purpose, I pass a screw 10 through the movable jaw 7, at a point in close proximity to the pivotal or hinge point of the jaw; the inner end, or point of the screw bears against the approximate face of the body 2, and thus limits the biting or gripping action of jaw 7. It will be readily understood that this construction admits of an adjustment whereby the wrench may be made to conform to various sizes of pipe. Screw 10 further serves as a trigger or finger piece for operating or opening jaw 7.

Having thus described my invention, what I claim as new and desire to secure by Letters Patent is.

1. In a pipe-wrench, a unitary structure consisting of a resistance jaw, a body-portion and a handle, there being ears upon said body-portion adapted to the mounting or attachment of a movable pressure jaw, there being also a recess formed in said body between said ears, a movable pressure jaw attached by one of its ends to said ears, the other end of said jaw being in juxtaposition to said first mentioned jaw, there being a lug upon said movable jaw approximate to the pivotal point thereof extending into said recess, an actuating block seated in said recess and adapted to engage said lug, a spring adapted to bear upon one end of said block for the purpose set forth, and adjustable means for limiting the gripping action of said movable jaw.

2. In a pipe-wrench, a unitary structure consisting of a main resistance jaw, a body portion and a handle, there being ears upon said body portion adapted to the mounting or attachment of a movable pressure jaw, there being also a recess formed in said body between said ears, in combination with a movable pressure jaw attached by one of its ends to said ears, the other end of said jaw being in juxtaposition to said first men-

2
tioned jaw, there being a lug upon said movable jaw, approximate to the pivotal point thereof, extending into said recess, an actuating block seated in said recess and adapted to engage said lug and a spring adapted to bear upon one end of said block, for the purpose set forth.

In testimony whereof I affix my signature in presence of two witnesses.

CHARLES E. ADAMS.
